(Cl. D85—2)

To all whom it may concern:

Be it known that I, Paul J. Qualls, a citizen of the United States of America and a resident of Bremen, in the county of Fairfield and State of Ohio, have invented a new, original, and ornamental Design for an Ash Tray or Similar Article, of which the following is the specification, reference being had to the accompanying drawing, forming a part thereof.

Figure 1 is a perspective view of an ash tray or similar article showing my new design.

Figure 2 is a top plan view of the article shown in Figure 1.

Figure 3 is a side view in section taken along line 3—3 of Figure 2.

I claim:
The ornamental design for an ash tray or similar article, substantially as shown.

PAUL J. QUALLS.
